UNITED STATES PATENT OFFICE.

WILLIAM G. DRAKE, OF DONORA, PENNSYLVANIA.

STOVEPIPE-FASTENER.

SPECIFICATION forming part of Letters Patent No. 745,003, dated November 24, 1903.

Application filed November 22, 1902. Serial No. 132,464. (No model.)

To all whom it may concern:

Be it known that I, WILLIAM G. DRAKE, a citizen of the United States, residing at Donora, in the county of Washington and State 5 of Pennsylvania, have invented a new and useful Stovepipe-Fastener, of which the following is a specification.

This invention relates to devices for fastening stovepipes in the flue-openings of chimneys or other apertures through which the pipe passes, and has for its object to provide a simply-constructed and easily applied and adjusted device whereby the pipe may be securely fastened in place in position to be readily detached and adjusted to any thickness of chimney, wall, or other support; and the invention consists in certain novel features of construction, as hereinafter shown and described, and specifically pointed out in the 15 claims.

In the drawings illustrative of the invention, in which corresponding parts in the several figures are designated by like reference characters, Figure 1 is a side elevation of the 25 device applied. Fig. 2 is a transverse section on the line II II of Fig. 1. Fig. 3 is a detached perspective view, enlarged, of one of the lever-clamps.

The improved device may be attached to 30 any size of stovepipe and to stovepipes passing through partitions or walls or into chimneys or supported in any other desirable manner, and for the purpose of illustration the device is shown applied to a section of stovepipe inserted in the ordinary manner into the flue-opening of a chimney, a portion of a chimney being indicated at 10 and forming a support for the pipe, a section of which is shown 35 at 11, of the ordinary construction, the pipe being shown inserted through the usual flue-opening of the chimney.

The improved device consists in a flat relatively thin bar or plate 12, adapted to be inserted through the flue-opening between the 40 pipe 11 and the flue lining or thimble and with its inner end folded over, as shown at 45 13, to form an offset projecting laterally from the plate or bar and the extremity secured to the plate, as by a rivet 14, the offset 13 serving as a stop to prevent the withdrawal of the 50 plate 12 while the pipe is in position within the flue-opening.

Attached by a handle member 15 to the free end of the bar 12 is another bar 16 relatively thicker than the bar 12, but preferably 55 of the same width and forming a continuation thereof, as shown.

Partially embracing the pipe opposite the bar 16, preferably near its outer or free end, are two lever members 17 18, conforming to 60 the curvature of the pipe and extending below its center, so that they enclose more than one-half of the circumference of the pipe, as indicated in Fig. 2, and forming clamp-levers adapted to be compressed into engagement 65 with the pipe.

The adjacent ends of the clamp-levers 17 18 are inclined inwardly and outwardly away from the pipe 11, as shown in Fig. 2, and with apertures at the junctures of the inclined and 70 curved portions, the apertures adapted to receive the bent-up ends 21 22 of the coupling-rod 23, by which means the clamp-levers will be movably coupled and spaced apart with reversely-inclined adjacent portions. 75

The inclined portions 19 20 will be formed with recesses longitudinally of the inclined portions, as indicated in Fig. 3. The coupling-rod 23 will pass beneath the relatively thick connecting-bar 16, as indicated, and is provided with upwardly-extending spaced ears or lugs 23', forming guides between which the bar 16 slides and which prevent the lateral displacement of said bar, the bar being thus always connected with the levers 17 and 18 85 and held in position beneath a cam-lever, hereinafter described.

The clamp-levers 17 18 will preferably be formed substantially in U shape in cross-section, the bottom portions being curved to conform to the outlines of the stovepipe and the leg portions of the U-sections forming side walls to the levers, as indicated, by which means the levers are greatly strengthened and enabled to resist the pressure to which they 95 will be subjected without unduly increasing the weight or bulk.

The pipe 11 will be surrounded with the usual collar 24 at the point where it enters the flue, and connecting this collar and the lever-clamps 17 18 are tie-bars 25, preferably riveted by their ends, respectively, to the collar and to the clamp-levers, as indicated at 26 27. One of these tie-bars will be connected to each 100

of the clamp-levers, as indicated in Fig. 2, upon opposite sides of the pipe.

Fitting into the recesses in the inclined ends 19 20 of the clamp-levers 17 18 are wedge-blocks 28 29, and between these wedge-blocks is pivotally supported at 30 a cam-lever 31, the operative end 32 of the cam-lever adapted to forcibly engage the connecting-bar 16, which passes beneath the wedge-blocks and 10 above the coupling-bar 23, as shown. By this arrangement it will be obvious that when the cam-lever is moved into the position indicated by dotted lines in Fig. 1 the clamp-levers will be released by the depression of 15 the wedge-blocks and the disconnection of the end 32 from the plate 16. If, however, the cam-lever be reversed in position or turned, as shown in Fig. 1 in full lines, the operative end 32 will forcibly compress the plate 16 20 upon the coupling-bar 23 and the pipe 11, while at the same time the wedge-blocks 28 29 will be forcibly moved away from the pipe and throw the outer ends of the inclined portions 19 20 apart and correspondingly compress the longer ends of the curved portions 17 18 forcibly against the outer surface of the pipe, and as those longer ends extend below the center of the pipe the device will be firmly clamped to the pipe, as will be obvious. By 25 30 this simple means the whole device may be firmly clamped to the pipe and retain the pipe in position relative to the flue-opening, or other aperture through which it is passed, the offset 13 preventing longitudinal movement 35 in one direction, and the connecting-bars 25 preventing longitudinal movement in the opposite direction, while the clamp-levers 17 18 firmly engage the whole device to the pipe.

When the device is to be applied, the collar 24, with the clamp-levers 17 18, coupled by the bar 23, and the wedge-blocks 28 29 and cam-lever 31, connected thereto by the bars 25, will be inserted over the end of the pipe which is to enter the flue or pass through the 40 wall or partition, the connected bars 12 16 having first been placed in position upon the pipe, with the offset end 13 extending beyond the end of the pipe. The extended portion of the bar 12, with its offset end, is then passed 45 through the flue-opening or other aperture in advance of the pipe until the offset 13 is in position upon the opposite side of the aperture, when the pipe can be readily inserted, with the portion 12, between the pipe and the 50 interior of the opening, the relative thinness of the portion 12 permitting this action. The collar 24 with its connected clamp-levers and attachments are then moved longitudinally of the pipe, with the relatively thick portion 55 60 of the connecting-rod between the cam-lever and the pipe and preferably above the bar 23, as shown. The connected bar 12 16, which forms the connecting means between the clamp-levers 17 and 18 and the pipe-support 65 port 10, is then adjusted longitudinally of the pipe until the offset 13 closely engages the interior of the flue or other aperture and the

cam-lever 31 moved into operative position, as shown in Fig. 1, which action firmly locks the parts together, as before described. By 70 this simple arrangement the pipe may be very quickly and readily locked in position and firmly supported relative to the flue or other opening and all danger of the displacement of the pipe averted. 75

The parts are all simple in construction and can be manufactured very cheaply and readily applied by persons without previous skill and will be found very convenient and useful for the purposes described. 80

The parts may be modified in minor particulars without departing from the principle of the invention or sacrificing any of its advantages.

The clamp-levers 17 18 will preferably be 85 of sheet metal pressed or stamped into shape, but may be constructed of other metal, if preferred.

Having thus described the invention, what is claimed is—

1. A stovepipe-fastener consisting of a connecting-bar having means for engaging a flue and disposed between the pipe and flue-opening, reversely-disposed clamp-levers for movably engaging the pipe adjacent to said connecting-bar, means for movably coupling the adjacent ends of said levers, and means operative between said clamp-levers for distending them and forcibly clamping said bar and levers simultaneously upon the pipe, substantially as described. 90 95 100

2. A stovepipe-fastener consisting of a connecting-bar formed of a relatively thin section and a relatively thick section movably united and provided with a handle at the 105 point of juncture with the thin portion disposed between the pipe and flue-opening and having an offset engaging the interior of the flue, clamp-levers reversely disposed and engaging the pipe adjacent to the thicker portion of said connecting-bar, means for coupling said levers by their adjacent ends, and means operative between said clamp-levers for forcibly distending them and clamping said bar and levers simultaneously upon the 110 115 pipe, substantially as described.

3. A stovepipe-fastener consisting of a connecting-bar having an offset engaging the interior of the flue and disposed between the pipe and flue-opening, reversely-disposed clamp-levers movably engaging the pipe adjacent to said connecting-bar, means for movably coupling the adjacent ends of said levers, means operative between said levers for forcibly clamping said bar and levers simultaneously upon the pipe, and means connecting the free ends of said clamp-levers to the flue-breast, for bracing them and holding them spaced from said flue-breast, substantially as described. 120 125 130

4. A stovepipe-fastener consisting of a connecting-bar having an offset engaging the interior of the flue and disposed between the pipe and flue-opening, reversely-disposed

clamp-levers movably engaging the pipe adjacent to said connecting-bar, means for movably coupling the adjacent ends of said lever, means for forcibly clamping said bar and levers simultaneously upon the pipe, a collar encircling the pipe at the flue-breast, and connecting-rods between said levers and collar, for bracing said levers and holding them spaced from said collar, substantially as described.

5 5. A stovepipe-fastener consisting of a connecting-bar having an offset engaging the interior of the flue and disposed between the pipe and flue-opening, reversely-disposed clamp-levers movably engaging the pipe adjacent to said connecting-bar, a coupling-rod movably uniting the adjacent ends of said levers and disposed transversely of said connecting-bar, and means operative between 15 said clamp-levers for forcibly distending them and clamping said connecting-bar and coupling rod upon said pipe and likewise clamping said levers to the pipe, substantially as described.

20 6. A stovepipe-fastener consisting of oppositely-disposed clamp-levers movably enclosing the stovepipe and with their adjacent ends reversely inclined, a connecting-bar movably attached to the flue, means for movably coupling the adjacent ends of said clamp-levers, reversely-disposed wedge-blocks movably engaging the adjacent inclined ends of said levers, and a cam-lever movably engaging said connecting-rod and 25 movably connected to said wedge-blocks, whereby the operation of said cam-lever will forcibly clamp said connecting-bar and clamp-levers simultaneously upon the stovepipe, substantially as described.

30 7. A stovepipe-fastener consisting of oppositely-disposed clamp-levers movably enclosing the stovepipe with their adjacent ends reversely inclined and with apertures at the juncture of the inclined portions and the body of the lever, a coupling-rod with its ends bent into engagement with the levers through said apertures, a connecting-rod disposed transversely of said coupling-rod and movably engaging the flue-opening, reversely-disposed wedge-blocks movably engaging the adjacent inclined ends of said levers, a cam-lever movably engaging said 35 connecting-rod and movably connected to said wedge-blocks, whereby the operation of said cam-levers will forcibly clamp said connecting-bar and clamp-levers simultaneously upon the stovepipe, substantially as described.

40 8. A stovepipe-fastener consisting of oppositely-disposed clamp-levers movably en-

clasping the stovepipe and with their adjacent ends reversely inclined and provided with recesses within said inclined ends, a connecting-bar movably attached to the flue and extending between said levers, reversely-disposed wedge-blocks movably engaging the recesses in the adjacent inclined ends of said levers, and a cam-lever movably engaging said connecting-bar and movably connected to said wedge-blocks, whereby the operation 65 of said cam-lever will forcibly clamp said connecting-bar and clamp-levers simultaneously upon the stovepipe and prevent lateral movement, substantially as described.

9. A stovepipe-fastener consisting of oppositely-disposed clamp-levers for movably engaging a pipe and with the adjacent ends reversely inclined, means for connecting said levers to a pipe-support, reversely-disposed wedge-blocks between the adjacent ends of 70 said levers, and a cam-lever movably connected between said wedge-blocks and adapted to operatively engage said connecting means, whereby said clamp-levers and connecting means may be simultaneously 75 clamped to the pipe, substantially as described.

10. A stovepipe-fastener consisting of oppositely-disposed clamp-levers movably engaging the pipe and with the adjacent ends 80 reversely inclined, connecting means between said levers and the support for the pipe, reversely-disposed wedge-blocks movably engaging said inclined ends, and means operatively engaging said wedges and connecting 85 means, whereby the levers and connecting means are simultaneously clamped to the pipe, substantially as described.

11. A stovepipe-fastener consisting of a connecting-bar having an offset formed by 90 folding the end of the bar over and connecting the extremity to the body thereof, and engaging the interior of the flue and disposed between the pipe and flue-opening, reversely-disposed clamp-levers movably engaging the 95 pipe adjacent to said connecting-bar, means for movably coupling the adjacent ends of said levers, and means operative between said clamp-levers for distending them and forcibly clamping said bar and levers simultaneously upon the pipe, substantially as described.

In testimony that I claim the foregoing as my own I have hereto affixed my signature in the presence of two witnesses.

WILLIAM G. DRAKE.
